PUMP PLUNGER

Walter A. O'Bannon, Tulsa, Okla.

Application July 15, 1940, Serial No. 345,563

8 Claims. (Cl. 309—4)

This invention relates to pumps for oil and similar fluid producing wells, and more particularly to a plunger for such pumps.

Pumps of this character include a working barrel reciprocated over a fixed plunger, or a plunger reciprocable within a fixed barrel, to draw in a fluid charge upon upstroke of the movable member and to transfer the fluid charge into the well tubing upon the downstroke, which charge is displaced subsequently to the succeeding upstroke. Due to the abrasive matter usually contained in the fluid and the difficulty of maintaining a seal by rings, the primary seal between the stationary and working members is largely through an extended working surface therebetween brought about by making the members of relatively long length. However, it is necessary to provide a certain operating clearance between the working parts, with the result that the well fluid works therebetween by reason of the vacuum effected within the barrel upon upstroke of the movable member. This in itself is not objectionable as the fluid tends to make a seal, but the well fluids usually contain a considerable amount of salt water or other fluid having electrolytic properties, with the result that electrolysis occurs between the pump members, causing their rapid deterioration. This is especially aggravated in the case of working barrel pumps because the salt water, being of heavier specific gravity, settles into the space between the tubing and the working barrel and is trapped therein, so that the working barrel is being constantly reciprocated in a concentrated electrolyte solution.

It is believed that this destructive action is set up through a current generated responsive to reciprocation of the movable member relatively to the stationary member, and this current, with the electrolyte, causes reduction of the metal of which the plunger is constructed. In any event, the metal parts become pitted and the reciprocatory action hastens their destruction.

It is, therefore, a principal object of the present invention to provide a plunger construction which obviates this difficulty so that a pump may be operated in such fluids for longer periods of time and thereby reduce replacement costs, as well as delays and inconvenience incidental to removal and replacement of the pump.

A further object of the invention is to provide a pump plunger construction which makes a more effective seal with the barrel so as to retard leakage of fluid and particularly that portion thereof producing the electrolytic action.

In accomplishing these and other objects of

the invention, as hereinafter pointed out, I have provided improved details of structure, the preferred form of which is illustrated in the accompanying drawings, wherein:

Fig. 1 is a vertical section through a well tubing containing a pump constructed in accordance with the present invention, the working barrel and valve cages being shown in section.

Fig. 2 is an enlarged vertical section through the pump plunger.

Fig. 3 is a cross-section on the line 3—3 of Fig. 2.

Fig. 4 is a longitudinal section through a modified form of pump plunger which embodies features of the present invention.

Fig. 5 is a cross-section on the line 5—5 of Fig. 4.

Fig. 6 is a longitudinal section through a further modified form of pump plunger embodying the features of the present invention.

Fig. 7 is a horizontal section on the line 7—7 of Fig. 6.

Referring more in detail to the drawings:

1 designates a well tubing that extends from 25 a point below the level of fluid collecting in the well to the top thereof, and forming a duct through which the fluid is lifted responsive to operation of a pump 2.

In the illustrated instance, the pump 2 includes 30 a stationary plunger 3 and a reciprocatory barrel 4, movable over the plunger responsive to actuation of a pump unit having connection with the barrel by sucker rods 4'. The plunger 3 includes an anchor or hold-down 5 wedgingly seated in the tapering bore 6 of a shoe 7 carried by the well tubing.

Extending upwardly from the anchor 5 is a 35 plunger tube 8 including a lower section 9 suitably connected with the anchor 5 as at 8' and having its upper end adapted to be connected with the threaded lower end 10 of an upper section 11 which carries the plunger body elements having contact with the inner surface of the barrel 4, as later described. The upper end of the section 11 is threaded, as at 12, to mount a valve seat fitting 13 carrying a valve 14.

The barrel 4 is reciprocable in coaxial relation over the plunger, and is of sufficient length to accommodate the length of the plunger plus the desired maximum working stroke of the pump. The upper end of the barrel carries the usual working valve 15, which cooperates with the valve 14 in controlling movement of the fluid responsive to reciprocation of the sucker rods.

On the upstroke of the working barrel, the

standing valve 14 unseats and a fluid charge is drawn into the space 16 between the upwardly moving working valve 15 and the valve 14. On the downstroke this fluid is trapped by the closed valve and is displaced through the working valve 15 into the well tubing 1. On the succeeding upstroke, the fluid in the tubing 1 is displaced by the upwardly moving barrel 4 so that a charge is passed from the top of the well. If the well contains salt water or water emulsions, they are of heavier specific gravity than the oil and settle into the space 17 between the working barrel and well tubing. Upon the upstroke, a vacuum is drawn in the upper end of the working barrel, which, supplemented by hydrostatic head of well fluid in the tubing, causes the solution to work its way upwardly between the working barrel and plunger. The plunger is, therefore, continuously operating within an electrolytic solution, with the result that the generated current causes electrolysis of the metal parts, leaving them pitted and subject to rapid wear.

In order to overcome this difficulty, I have provided a plunger construction so designed that electrolytic action is resisted between the working barrel and plunger or the component parts thereof, as now to be described. Sleeved upon the upper tubular section 11 is a series of sleeve-like sections 18, each having an outer circumference to be snugly slideable within the barrel to reduce as much as possible the clearance therebetween. The sleeve-like sections may be formed of metal, in which instance they are spaced from the tube 11 by a softer metal 19, higher in the electrochemical series than the metal composing the barrel 4, the tube 11, or the sleeve-like sections 18. The ends of the sections are also spaced apart by rings 20 of the same or similar soft metal, so that the sections composing the plunger are entirely separated from each other by such metal. The sections are retained in abutting contact with the separating rings and from shifting movement on the tube-like body 11 by a nut 21, which cooperates with the seat fitting 13. Similar washers 22 and 23 are inserted between the endmost sections and the retaining members 12 and 21, as clearly shown in Fig. 2. The sleeve-like sections may be provided with annular grooves 24 extending circumferentially thereof to form oil seals with the inner surface of the working barrel.

With this construction, any electrochemical action taking place between the parts of the plunger will be resisted by the inserted metal. Any electrolytic action which does occur results in decomposition of the softer material rather than the working surfaces of the sleeve-like sections and forms a dielectric as a primary product of corrosion incidental to said decomposition and resists galvanic action responsive to metal contact. Therefore, the sleeve-like sections retain their original properties and maintain the desired seal with the inner surface of the working barrel.

I have also found that the sleeve-like sections may be formed of dielectric composition such as one of the synthetic resins, in which case the sleeve-like sections 25 (Fig. 4) are sleeved directly on the tube-like body of the plunger and retained in end to end engagement with oil seal rings inserted therebetween, indicated at 26. These rings may include flexible cups 27, having inwardly extending annular flange portions 28 clamped between spacers 29 and 30, whereby sealing lips 31 of the rings are retained in position to maintain seal with the inner surface of the working barrel.

The spacers 29 are preferably recessed, as at 32, so as to allow the necessary movement of the sealing lips.

In Fig. 6 the tube-like body of the plunger is covered with the outer sleeve 33 formed of dielectric or insulating material. This sleeve may be coextensive with the length of the plunger body or formed in sections which are retained in abutting contact with each other. With some of the more brittle dielectric materials, it may be desirable to form the dielectric material directly upon a metallic sleeve somewhat similar to the structure used in the form of the invention illustrated in Fig. 2. The dielectric sleeves may be sized to fit closely within the working barrel so as to reduce leakage and provide a long wearing surface which is less abraded by the fluid incidental to reciprocation of the barrel. The sleeve being made of dielectric material, there is no electrolytical action which can take place between the sleeve-like sections and the tubular body of the plunger or the working surface of the barrel.

From the foregoing it is obvious that I have provided a plunger construction which is not subject to rapid deterioration incidental to electrolytic action caused by the presence of an electrolytic solution in the well fluid. Consequently, a pump equipped with such a plunger will operate efficiently for long periods of time, and shutdowns for repairs will be less frequent than in former constructions where the affects of electrolysis are not considered.

What I claim and desire to secure by Letters Patent is:

1. A composite pump plunger for pumps handling fluids having electrolytic characteristics, said plunger being formed of metal parts subject to electrochemical decomposition when operating in said fluids, said parts having facing surfaces and metallic spacing means having opposite faces respectively contacting the facing surfaces of said metal parts of said plunger and having a property relative to the electrochemical properties of the plunger parts to be the metal affected by electrolytic action.
2. A pump plunger including, a body member, a sleeve-like member on said body member, said body member and sleeve-like member normally being subject to electrochemical decomposition when used in connection with fluids having electrolytic characteristics, and a metallic insert between said sleeve-like member and body member having a property relative to the electrochemical properties of the sleeve-like member and body member of being the metal affected by electrolytic action.
3. A pump plunger including, a body member, a plurality of sleeve-like sections on said body member normally being subject to electrochemical decomposition when used in connection with fluids having electrolytic characteristics, an insert between said sleeve-like sections and the body member, and similar metal inserts between said sleeve-like sections, said inserts being formed of a metal having a property relative to the electrochemical properties of the sleeve-like sections of being the metal affected by electrolytic action.
4. A pump plunger for operating in fluids having electrolytic characteristics including, a body member and a sleeve member on the body member, and a readily decomposable metal between the body and sleeve member to form a dielectric member between the body and sleeve members as a primary product of corrosion when the

plunger is subjected to electrolytic decomposition by said fluid.

5. A pump including, cylinder and plunger members formed of metal ordinarily subject to decomposition when handling fluids having electrolytic characteristics, and a protective metal carried on one of said members having the property of being corroded responsive to metal contact with said member whereby said corrosion forms a dielectric on said member to resist decomposition of said members when subject to electrolytic action.

6. In a pump, cylinder and plunger members formed of metal and one movable with respect to the other, a sleeve member having fixed mounting on one member and slideable engagement with the other member, and means interposed between said sleeve member and the member on which said sleeve member is fixed for resisting deterioration of said members by galvanic action responsive to metal to metal contact of said members, said means having a property relative to that of the contacting members of being the one subject to decomposition by any galvanic action which tends to occur between said members.

7. In a pump, a cylinder, a plunger body member in the cylinder, said cylinder and plunger body member having relative movement, a plurality of sleeve-like sections having fixed mount-

ing on said body member and sliding engagement with the cylinder member responsive to said movement, and means interposed between said sleeve-like sections and the body member for resisting deterioration of said sections to galvanic action responsive to the metal to metal contact of said sleeve-like sections with the cylinder and plunger body member, said means having a property relative to that of the contacting members of being the one subject to decomposition by any galvanic action which tends to occur between said members.

8. In a pump, a cylinder, a plunger body member in the cylinder, said cylinder and plunger body member having relative movement, a plurality of sleeve-like sections having fixed mounting on said body member and sliding engagement with the cylinder member responsive to said movement, and spacing means interposed between said sleeve-like sections and the body member and between adjacent ends of said sections for resisting deterioration of said members by galvanic action responsive to the metal to metal contact, said means having a property relative to that of the sections and cylinder of being the one subject to decomposition by any galvanic action which tends to occur between said members.
